Inventor
Arthur C. Griewank

UNITED STATES PATENT OFFICE.

ARTHUR C. GRIEWANK, OF OAKLAND, CALIFORNIA.

CONCRETE RAILROAD TRACK.

1,413,983.

Specification of Letters Patent. Patented Apr. 25, 1922.

Application filed January 4, 1919. Serial No. 269,594.

To all whom it may concern:

Be it known that I, ARTHUR C. GRIEWANK, a citizen of the United States, residing at 927 Grand Avenue, in the city of Oakland, in 5 the county of Alameda and State of California, have invented a new and useful Concrete Railroad Track, of which the following is a specification.

The object of the present invention is to 10 provide a novel construction of railroad track, which, while made of materials that are as cheap as those used at present time, will be permanent and cost less to maintain than the present construction, while being 15 able to withstand shocks, strains, and stresses to which such tracks are ordinarily subjected. This construction will prevent accidents which occur on the present construction.

In the accompanying drawings Figure 1 is 20 a plan of a reinforced concrete track system constructed in accordance with my invention, Figure 2 is a longitudinal sectional view of the same on the line 3—3 of Figure 1; Figure 3 is a longitudinal sectional view 25 of the same on the line 4—4 of Figure 1; Figure 4 is a longitudinal sectional view of the same on the line 5—5 of Figure 1; Figures 5 and 6 are sectional views of expansion joints; Figure 7 is a transverse sectional 30 view of the track on the line 2—2 of Figure 1; Figure 8 is a transverse sectional view of the same on the line 1—1 of Figure 1; Figures 9 and 10 are transverse sectional views on the line 6—6 of Figure 1 with different 35 types of rail; Figures 11, 12, 13 and 14 are large transverse sectional views on the line 6—6 of Figure 1 with different types of rail.

Referring to the drawing, Figure 1 indicates a railroad track of concrete, or reinforced concrete, with cross ties 2. As shown at 5 the cross ties may project beyond the edge of the stringer 1, or continuous longitudinal ties 1 with a metallic wearing surface 3, secured to 1 with clips and bolts 4. 40 In Figures 2 and 3 are shown top reinforcing metal 7 and bottom reinforcing metal 6 in cross ties 2; in Figures 3 and 4 are shown top reinforcing metal 9 and bottom reinforcing metal 8 and diagonal reinforcing metal 50 10 in the longitudinal ties or girders 1. Figure 5 and Figure 6 show expansion joints which may or may not be used; 11 in Figure 5, and 12 in Figure 6 is an elastic substance which will separate the stringers 1 in Figure 55 1 into two parts while being constructed and which will allow the members to expand or

contract with change of temperature; 9 and 8 indicate top and bottom reinforcing metal as continuous at 11 and 12 in Figures 5 and 6 without a break.

In Figures 7 and 8 are shown cross ties 2, metallic wearing surfaces 3, longitudinal ties or girders 1, top reinforcing metal 9, bottom reinforcing metal 8, diagonal reinforcing metal 10; metal clips 4 and bolts for fastening metallic wearing surfaces 3 to the girders 1; 13 indicates a depression or recess in the longitudinal girders or ties 1, for the flanges of car wheels. In Figure 8 is shown top and bottom reinforcing metal 7 and 8 in cross 70 ties passing from 2 into the girders 1 without a break.

Figure 9 shows a cross section of a longitudinal tie or girder without the recess 13 and a metal wearing surface 3 of which 75 Figure 12 is an enlarged section in which 16 is a raised portion above 17 which is a horizontal member to distribute loads to the concrete; the raised portion 16 allows the flange to pass and provides for a surface on 80 which the face of the wheel is to bear and allow for wear. Figure 13 is a similar cross section to figure 12 with a vertical member 23 extending from the base 17 which is to act as a pavement retainer; 4 are the clips 85 which secure the metallic wearing surface to the concrete ties and which allow the metallic wearing surface to move longitudinally independent of the concrete ties while still held securely to it. In Figure 10, 3 is a metallic wearing surface composed of an ordinary T rail fastened to the concrete tie with clips 4. Figure 11 is an enlarged sectional view of the longitudinal tie or girder 1 and metallic wearing surface 3, as shown in Figures 7 and 8. 8, 9 and 10 show reinforcing metal rods; 4 indicates clips as in Figure 12, 13 is a continuous longitudinal recess in the longitudinal tie or girder 1; 3 is a metallic wearing surface with two wings, 18 and 19, 90 extending in opposite directions, and 20 a vertical connecting member; 14 is a thickened or raised portion on wing 19 for the face or base of wheel to bear on and which will allow for wearing down; 15 is a raised 100 or thickened portion on vertical member 20, shaped to receive the flange of the car wheel, which allows for the wearing away of the same by the flange of the car wheel bearing against it; the recess 13 in the longitudinal 105 girder 1 in Figure 11 allows the vertical part 20 of the wearing surface 3, to bear

continuously against the girder 1, which will prevent the metallic wearing surface 3 from spreading. Figure 14 is a similar section to Figure 11 with a vertical member 22 extending from the wing 18 of the metallic wearing surface 3, which will act as a pavement retainer or guard rail. In Figures 7 and 8, 25 is rock ballast or fill on which the track is built. In Figures 4 and 14 are shown holes 24 in the vertical members 22 and 23 to allow clips to pass through to secure the metallic wearing surface 3 to the longitudinal tie or girder 1.

I claim:

- 15 1. A metallic wearing surface for a railroad track with two wings extending from a vertical member in opposite directions near its edges with a raised or thickened portion on the outside corner extending horizontally and vertically for a short distance.
- 20 2. A metallic wearing surface for a railroad track with two wings extending from a vertical member in opposite directions at its

edges with a raised or thickened portion on the outside of one corner, near the edge of 25 the wing extending from the opposite edge of the vertical member on which is the raised portion, a member extending vertically approximately at right angles to said horizontal wing.

30 3. A metallic wearing surface for a railway track, composed of a vertical member, wings extending in opposite directions therefrom, and an enlarged portion including a portion of the wing at the intersection of the 35 wing and the vertical member.

4. A metallic wearing surface for a railway track, with a wing and a vertical member and an enlarged portion at the intersection of the vertical member and the wing.

5. A metallic wearing surface for a railway track, with wings in opposite directions from a vertical member and an enlarged portion including the vertical member and wing.

ARTHUR C. GRIEWANK.
